UNITED STATES PATENT OFFICE

JOHN WHITCOMB, OF LAKEWOOD, OHIO, ASSIGNOR TO THE B. F. GOODRICH COMPANY, OF NEW YORK, N. Y., A CORPORATION OF NEW YORK

DESIGN FOR A HOT WATER BOTTLE

Application filed December 29, 1931. Serial No. 42,278. Term of patent 14 years.

To all whom it may concern:

Be it known that I, JOHN WHITCOMB, a citizen of the United States, residing at Lakewood, in the county of Cuyahoga and State of Ohio, have invented a new, original, and ornamental Design for a Hot Water Bottle, of which the following is a specification, reference being had to the accompanying drawing, forming a part thereof.

The accompanying drawing shows a side elevation of a hot water bottle embodying my new design, the reverse side of the bottle being plain.

I claim:
The ornamental design for a hot water bottle as shown and described.

JOHN WHITCOMB.
